Des. 186,727
Patented Nov. 24, 1959

186,727

COMBINED BAROMETER, THERMOMETER, AND HYGROMETER

Stephen E. Laszlo, Brooklyn, N.Y.

Application January 11, 1957, Serial No. 44,476

Term of patent 7 years

(Cl. D52—7)

FIG-1

FIG. 2

Figure 1 is a perspective view of a combined barometer, thermometer and hygrometer showing my new design; and

Figure 2 is an elevational side view of the combined barometer, thermometer and hygrometer shown in Fig. 1.

The characteristic features of the design reside in the design of the dial itself.

I claim:

The ornamental design for a combined barometer, thermometer and hygrometer, as shown and described.
